DESIGN FOR A FOLDABLE DISPLAY CONTAINER

Louis A. Gales, St. Paul, Minn.

Application September 2, 1942, Serial No. 108,107

Term of patent 14 years

To all whom it may concern:

Be it known that I, Louis A. Gales, a citizen of the United States, residing at St. Paul, in the county of Ramsey, and State of Minnesota, have invented a new, original, and ornamental Design for a Foldable Display Container, of which the following is a specification, reference being had to the accompanying drawing, forming part thereof.

Figure 1 is a front perspective view of a foldable display container in folded condition, showing my new design;

Figure 2 is a front elevational view;

Figure 3 is a rear elevational view;

Figure 4 is a side elevational view of the same; and

Figure 5 is a top plan view of my foldable display container in unfolded position.

I claim:

The ornamental design for a foldable display container, as shown.

LOUIS A. GALES.
